UNITED STATES PATENT OFFICE.

FRIEDRICH A. MEHMEL, OF STRALSUND, PRUSSIA, GERMANY.

ORGAN-ACTION.

SPECIFICATION forming part of Letters Patent No. 224,457, dated February 10, 1880.

Application filed November 26, 1879.

To all whom it may concern:

Be it known that I, FRIEDRICH ALBERT MEHMEL, resident of Stralsund, Prussia, Empire of Germany, have invented new and useful 5 Improvements in Chests of Sound-Boards for Organs and similar musical works, of which the following is a specification.

The invention has for its object an arrangement of mechanism whereby the stops are 10 made the primary part or most important element and the key-board mechanism the secondary or subordinate part of an organ or other wind-instrument, as hereinafter described, and shown by the accompanying drawing, in which—

15 A is the wind-chest; a a, the air-chamber therein; b b, the channels or air-ducts formed in the bearers B, which conduct the air to the pipes. 20 C C are the valves binged to the bearers B, and D D are lever-supporting bars that in their normal position of rest are tilted, as shown, by one of them. These lever-supports are hinged to the supporting-blocks d by 25 means of hinges d', and are connected to the stop pull-bars E by means of the pivoted angle-levers e and the push-wires e', which latter are pivoted to the butts F' upon the under side of the hinged bars D, the degree 30 of elevation or depression being regulated by means of the thumb-nuts f'. Each hinged bar D has a projection, d², upon which is pivoted an angle-lever, G, adapted to operate the valves C. The lower end of the lever G is 35 perforated, and through this perforation passes the connecting-wire g, which connects the lever with the key-bar H, said lower end of the lever G being held in proper position and adjusted by means of the thumb-nuts g'.

40 The outer end of the key-bar H is connected, by means of a wire, h, and a thumb-nut, h', to the lower end of the arm l' of a three-armed lever, L, pivoted at l^x upon the supporting-block L'.

45 To the outer end of the arm l of the lever L the pull-wire M is connected, which, in its turn, is connected in any suitable or preferred manner with its respective key, (not shown in the drawing,) while the arm l' of said lever L 50 carries a counter-weight, L², which serves to bring the valve-levers G and the keys back into their normal position of rest when said

keys are relieved from pressure, the weight resting upon a bracket or seat, A², secured to the frame of the wind-chest A.

55

A' is the base-plate of the wind-chest, made removable, and A³ are removable heads to the air-chamber, applied air-tight in any convenient or preferred manner, so as to furnish proper means of access to the above-described 60 mechanism located within said chamber, either for adjustment or repair.

The operation of the mechanism is as follows: The stops being the primary element, when one of them is pulled the hinged lever-supports of that stop are tilted downward through the action of the stop-bar E upon the angle-lever e and push-wire e', and all the valve-levers corresponding with this stop are brought in a position with their upper or actuating extremities in contact, or nearly in contact, with the projecting faces of their respective valves C. If, now, the secondary element is brought into action—that is to say, if one or more of the keys in this stop are depressed—their bars H are moved to the right 70 through the action of the three-armed levers L, said bars also moving the lower arm of the valve-levers G in the same direction, while the upper arm of said levers is moved in a reverse 75 direction to open their corresponding valves C and admit the air to the pipes, as will be readily understood and as plainly shown by the accompanying drawing.

Having now described my invention, what I claim, and desire to secure by Letters Patent, is—

1. The combination, with the wind-chest, its air ducts and valves, and the stop pull-bars E, of the hinged lever-supports D, levers G, 90 push-wires e', and the angle-levers e, arranged to operate as and for the purpose specified.

2. The combination, with the wind-chest, its air ducts and valves, and the pull-wires M, of the three-armed lever L, bar H, rods g, and 95 levers G, arranged to operate substantially as specified.

In witness that I claim the foregoing I have hereunto set my hand this 11th day of October, 1879.

FRIEDRICH ALBERT MEHMEL.
